(57) CLAIM

The ornamental design for a sock, as shown and described.

DESCRIPTION

FIG. 1 is a perspective view of a sock showing my new design;

FIG. 2 is a right side view;

FIG. 3 is a left side view;

FIG. 4 is a front view;

FIG. 5 is a back view;

FIG. 6 is a top view; and,

FIG. 7 is a bottom view.

The evenly-spaced dashed lines depict stitching and form part of the claim.

The dash dot lines depict a boundary line of the sock and form no part of the claimed design.

The dash dot dot lines depict environmental matter and form no part of the claimed design.

1 Claim, 3 Drawing Sheets
